UNITED STATES PATENT OFFICE

HARVEY E. MORROW, OF NEW LONDON, IOWA

WINDOW SHADE TRIMMER

Application filed June 20, 1930. Serial No. 462,661.

Window shades are generally marketed in standard sizes, including rollers and fabric, and are frequently required to be trimmed to fit windows not conforming to standard widths.

Therefore, the primary object of this invention is the provision of a machine for trimming window shades quickly, accurately, and with a smooth even edge.

10 The machine includes a pair of brackets, a rod supported by the brackets, a third bracket adjustable on the rod between the main brackets, and a blade adjustable along the length of the rod to trim the shade to the required width.

While the drawings illustrate a preferred embodiment of the invention, it is to be understood that in adapting the means to meet specific needs and requirements, the design may be varied and changes in the minor details of construction may be resorted to within the scope of the invention as claimed without departing from the spirit thereof.

25 For a full understanding of the invention and the merits thereof, reference is to be had to the following description and the drawings hereto attached, in which:

Figure 1 is a top plan view of a window shade trimmer embodying the invention, parts being broken away and showing a window shade in position to be trimmed.

Figure 2 is a front view of the trimmer, parts being broken away.

Figure 3 is a sectional view on the line 3—3 of Figure 2.

Figure 4 is a sectional view on the line 4—4 of Figure 2.

Corresponding and like parts are referred to in the following description and designated in the several views of the drawings by like reference characters.

The trimmer comprises a pair of brackets 1 and 2 and a rod 3 supported thereby and attached thereto in any determinate way.

45 The outer ends of the brackets 1 and 2 are offset inwardly and the intermediate portions are formed with openings to receive the usual journals of a shade roller 4.

A third bracket 5 is adjustable lengthwise of the rod 3 and is retained in place by

means of a spring clamp 6 and a stem 7, the latter engaging one of a series of openings 8 formed in the length of the rod 3. The spring clamp provides for ready detachment of the bracket 5 from the rod 3 and replacement of the bracket, as required. The stem 7 passes through the rod 3 and fixes the position of the bracket, whereas the spring clamp 6 holds the bracket to the rod when placed thereon. A shade of maximum width has its roller applied to the main brackets 1 and 2, the adjustable bracket 5 being removed. When trimming shades of a width less than the distance between the main brackets 1 and 2, the auxiliary bracket 5 is placed upon the rod 3 in position so that the roller of the shade to be trimmed may be applied to the bracket 5 and the bracket 2, as indicated most clearly in Figure 1 of the drawings.

The cutter consists of a blade 9 formed with a shank 10. Openings 11 are formed in the rod 3 adjacent an end thereof and receive the shank 10. The openings 11 are spaced apart a short distance to provide for adjustment of the cutter to meet requirements incident to trimming shades of standard sizes to meet existing conditions. The rod 3 usually consists of a tube and the openings 8 and 11 extend through opposite sides thereof. The openings 8 are disposed horizontally whereas the openings 11 have a vertical arrangement. Transverse slots 12 are formed in the top side of the tubular rod 3 and intersect the openings 11 formed therein. These slots 12 are of a size to accommodate the blade 9 so that it may be adjusted from one to another of the slots and openings. As indicated most clearly in Figure 4 of the drawings, the lower end of the blade 9 engages the inner wall of the tubular rod and supports the blade, lateral movement being prevented by the shank 10 passing through the opening formed in the bottom side of the rod.

The shade 13 to be trimmed has its roller fitted either to the main brackets 1 and 2 or to the auxiliary bracket 5 and main bracket 2, depending upon the width of the shade to be trimmed. The blade 9 is adjusted on the rod 3 to the required position, after which a

portion of the shade is unwound from the roller 4 and passed over the rod 3 and drawn forward against the edge of the blade 9 which cuts through the hem of the shade and 5 trims the latter to the required width, as will be readily appreciated. After the shade has been trimmed it is permitted to rewind upon the roller 4 which is removed from the brackets. The operation may be quickly and 10 conveniently performed and the edge bordering upon the cut is smooth. By having the brackets offset, provision is had for accommodating the ends of the shade roller which are usually exposed and extend beyond the 15 sides of the shade, as indicated in Figure 1 of the drawings. The device may be supported upon a wall or the like at any convenient height to admit of placing the shade roller in position and drawing the shade over 20 the rod 3 and against the cutting edge of the blade 9.

What is claimed is:

1. A trimmer comprising a tubular rod having a plurality of openings in the length 25 thereof and extending through opposite sides, said rod having transverse slots in one side intersecting the openings, and a blade formed with a shank adapted to pass through selected openings in the sides of the rod, the trans- 30 verse slots accommodating the blade.

2. A window shade trimmer comprising a rod provided in its length with transverse openings, brackets engaged with ends of the rod, a bracket adjustable longitudinally upon 35 the rod and together with one of the end brackets being adapted to support a roller, a shank carried by the adjustable bracket to engage a selected opening of the rod and hold the adjustable bracket in an adjusted 40 position longitudinally of the rod, a spring clamp carried by the adjustable bracket and adapted to engage about the rod to hold the bracket in place thereon, and a cutting blade carried by said rod and adjustable longi- 45 tudinally thereof.

3. A window shade trimmer comprising a pair of main brackets, a rod supported by the brackets, an auxiliary bracket adjustable on the rod between the main brackets, the 50 auxiliary bracket and one main bracket being adapted to support a roller in transverse spaced relation to the rod whereby a shade carried by the roller may be unwound therefrom across the rod, and a blade mounted 55 upon the rod for cutting the shade drawn from the roller across the rod.

4. A window shade trimmer comprising main brackets, a rod supported by the brackets, an auxiliary bracket on the rod and ad- 60 justable lengthwise thereof and together with one of the main brackets being adapted to rotatably support a shade roller, and a blade mounted upon the rod and adjustable in the length thereof whereby a shade drawn across 65 the rod from a roller may be cut by the blade.

5. A window shade trimmer comprising a pair of main brackets having corresponding ends offset inwardly, a rod attached to the offset ends of the brackets, an auxiliary bracket having an end portion offset laterally and engaged with the rod for adjustment longitudinally thereon; said brackets extending radially from the rod and adapted to support a roller in spaced parallel relation thereto, and a blade mounted upon the rod and adjustable along the length thereof whereby a shade drawn across the rod from a roller may be cut by the blade.

In testimony whereof I affix my signature.
